UNITED STATES PATENT OFFICE.

CHARLES PATRICK DOOLAN, OF GEBO, WYOMING.

RAIL-JOINT.

1,261,909.

Specification of Letters Patent. Patented Apr. 9, 1918.

Application filed September 24, 1917. Serial No. 193,005.

To all whom it may concern:

Be it known that I, CHARLES PATRICK DOOLAN, a citizen of the United States, residing at Gebo, in the county of Hot Springs, 5 State of Wyoming, have invented a new and useful Rail-Joint; and I do hereby declare the following to be a full, clear, and exact description of the invention, such as will enable others skilled in the art to which it applies to make and use the same.

The present invention relates to certain new and useful improvements in rail joints, and has for its object to provide a device of this character which embodies novel features 5 of construction whereby the abutting ends of a pair of rails can be held securely against both vertical and lateral displacement relative to each other, without the necessity of employing the usual splice bars.

Further objects of the invention are to provide a rail joint which is comparatively simple and inexpensive in its construction, which holds the rail ends securely together and will not work loose under the vibrations 5 incident to heavy traffic, and which is not liable to shear or break in the event of derailment.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a rail joint constructed in accordance with the invention.

Fig. 2 is a transverse sectional view taken on the line 2—2 of Fig. 1.

Fig. 3 is a transverse sectional view taken on the line 3—3 of Fig. 1.

Fig. 4 is a horizontal sectional view taken on the line 4—4 of Fig. 3.

Corresponding and like parts are referred to in the following description and indicated in all the views of the drawings by the same reference characters.

Referring to the drawings, which illustrate one embodiment of the invention, the numerals 1 and 2 designate the abutting ends of a pair of rails which are preferably of the standard cross section. The rail 1 is provided upon opposite sides of the web there-

of and also upon the upper surface of the basal flanges with integral outstanding longitudinally extending ribs 3, said ribs being provided with the threaded bores 4. The 60 ribs 3 on the web of the rail are preferably located adjacent the head thereof, while the ribs 3 on the base flange thereof are preferably located adjacent the web, and the bores 4 may have the inner sides thereof extending into what would be the regular cross section of the rail, thereby avoiding the necessity of making the ribs unnecessarily thick. The rear ends of the threaded bores 4 in the ribs 3 are preferably closed so as to 70 exclude dust and dirt therefrom. The opposite rail end 2 is provided with ribs 5 which correspond to the ribs 3 of the rail 1, said ribs 5 being provided with bores 6 which extend entirely through the same from end 75 to end. These ribs 5 are provided at intermediate points in their lengths with side openings 7 which intersect the bores and are adapted to provide a clearance space for the reception of a wrench or similar tool. The 80 portion of the bores 6 between the end of the rail and the side opening 7 are threaded, while the rear ends of the bores are not threaded. Bolts 8 are threaded in the bores 6 of the ribs 5 and the bores 4 of the corresponding ribs 3 to hold the rail ends securely together and prevent relative displacement thereof. These bolts 8 are each threaded for approximately two thirds or three fourths of their length from one end 85 thereof, the opposite end of the bolt being square, as indicated at 8^a, for engagement with a wrench to rotate the bolts. The bolts or rods 8 are inserted in position through the open rear ends of the ribs 5 on the rail ends 2 and screwed through the threaded portion of the ribs until they are flush with the ends of the rail 2, whereupon the end of the rail 1 is caused to abut against the rail 2 and the bolt or rod 8 threaded into the bore of the corresponding rib 3 on the rail 1 by continued rotation thereof. The side openings 7 in the ribs 5 enable the square ends 8^a of the bolts to be readily engaged by a wrench for manipulating the bolts at 90 any time, and the arrangement is such that the rail ends will be held securely together, even though there might be a slight loosening of the bolts. If desired, doors or closures 9 which are mounted upon the spring hinges 10 may be provided for the side openings 7 of the ribs, said doors serving to exclude

dust and dirt from the bores 6, and also having the inner faces 9^a thereof constructed to engage the square or polygonal portions 8^a of the bolts to lock them against accidental 5 rotation. It will be understood, however, that these doors or closures 9 can be readily swung outwardly into an open position when it is desired to engage the square portions 10 of the bolts 8 with a wrench for the purpose of manipulating the same.

Having thus described the invention, what I claim as new and desire to secure by Letters Patent, is:—

1. A rail joint including the abutting ends 15 of a pair of rails, each rail end being provided at the sides thereof with corresponding enlarged ribs which extend longitudinally and have threaded openings through the same, the ribs of one rail being provided 20 with side openings, and threaded tie bolts screwed into the openings of the corresponding ribs, said tie bolts being formed with polygonal portions which are accessible through the before mentioned side openings 25 in the ribs of one rail.

2. A rail joint including the abutting ends 30 of a pair of rails, each rail end being provided at the sides thereof with corresponding enlarged ribs which extend longitudinally and have openings therethrough, the rear ends of the ribs in one rail being closed, while the openings extend completely 35 through the ribs of the other rail end, the ribs being provided with side openings communicating therewith, and tie bolts insertible through the open rear ends of the ribs on the second mentioned rail and threaded for 40 engagement with the openings of the two sets of ribs, said tie bolts being formed with polygonal portions which are accessible through the side openings in the ribs of the second mentioned rail.

3. A rail joint including the abutting ends

of a pair of rails, each rail end being provided on opposite sides of its web and on the 45 upper faces of its base flanges with corresponding enlarged ribs which extend longitudinally of the rail ends and are provided with longitudinally threaded openings, the ribs of one rail being closed at the rear ends 50 thereof, while the longitudinal openings extend entirely through the ribs of the other rail, the said ribs being formed with side openings communicating with the longitudinal openings, and tie bolts insertible 55 through the open rear ends of the ribs of the second rail and adapted to have a threaded engagement with the openings of the corresponding ribs, said tie bolts being formed with polygonal ends which are accessible 60 through the side openings in the ribs of the second rail.

4. A rail joint including the abutting ends 65 of a pair of rails, each rail end being provided at the sides thereof with corresponding enlarged ribs which extend longitudinally of the rail and are formed with longitudinal openings, the ribs of one rail being provided with side openings communicating with the longitudinal openings, tie 70 bolts adapted to have a threaded engagement with the longitudinal openings of the two sets of ribs and formed with polygonal portions which are accessible through the side openings in the ribs of the second rail, 75 and closures for the side openings, said closures being constructed to engage the polygonal portions of the tie bolts to lock the tie bolts against rotation.

In testimony whereof I have signed my 80 name to this specification in the presence of two subscribing witnesses.

CHARLES PATRICK DOOLAN.
